UNITED STATES PATENT OFFICE.

JOSEPH E. DE WYNGAERT, OF NEWARK, NEW JERSEY.

DESIGN FOR A HEAD OF BROOCHES, SCARF-PINS, OR SIMILAR ARTICLES.

No. 38,918.

Specification for Design.

Patented Dec. 3, 1907.

Application filed September 3, 1907. Serial No. 391,276. Term of patent 7 years.

To all whom it may concern:

Be it known that I, JOSEPH E. DE WYNGAERT, a citizen of the United States, residing in the city of Newark, in the county of Essex and State of New Jersey, have invented a new, original, and ornamental Design for the Head of a Brooch, Scarf-Pin, or Similar Article, of which the following is a specification, reference being had to the accompanying drawings, forming a part thereof.

I claim:

The ornamental design for a head of a brooch, scarf-pin, or similar article, as shown.

JOSEPH E. DE WYNGAERT.
